MANUFACTURING COMPANY, OF MILWAUKEE, WISCONSIN, A CORPORATION OF
DELAWARE.

POLE AND METHOD OF CONSTRUCTING SAME.

1,369,765.

Specification of Letters Patent.

Patented Mar. 1, 1921.

Application filed August 28, 1918. Serial No. 252,126.

To all whom it may concern:

Be it known that I, ROBERT L. ALEXANDER, a citizen of the United States, residing at West Allis, in the county of Milwaukee and State of Wisconsin, have invented a certain new and useful Improvement in Poles and Methods of Constructing Same, of which the following is a specification.

This invention relates to magnetic field structures and the pole pieces thereof and a method of constructing the same. The invention may be applied in dynamo-electric machines and a particularly advantageous use of the invention is in large alternating current generators having revolving field structures.

In large machines in which revolving magnetic field structures are used having projecting pole pieces very considerable stresses arise chiefly by reason of centrifugal forces tending to pull the pole pieces away from the core in which they are fastened. It is usual to construct such pole pieces with a plurality of means for fastening the same to the core in order to give sufficient strength to resist the forces developed. One of the difficulties encountered in such a construction is that with the ordinary accuracy of workmanship the various fastening means do not assume the same share of the stresses developed and it has been proposed to construct pole pieces divided in several parts each one having its own individual fastening means. Here again it may occur that due to variations in accuracy of workmanship the various parts of the divided pole will not extend parallel to each other or in the desired relative directions as the case may be, and it is one of the objects of this invention to provide a method and means which will obviate these undesirable features.

Another object of the invention is the provision of a method and means for balancing centrifugal stresses arising in the pole tips where such are provided on the projecting pole pieces.

Another object of the invention is the provision of a method and means whereby such pole pieces may be cheaply and expeditiously manufactured. Other objects will appear hereinafter as the description proceeds.

The novel features of the invention will appear from this specification and the accompanying drawings which form a part thereof and all these novel features are intended to be particularly pointed out in the claims.

In Figure 1 is shown a field structure embodying the features of the invention, a fragment only of the revolving core being shown.

Fig. 2 shows a side elevation of one of the divided parts of the pole piece, the coil and core being shown in section along the line II—II.

Fig. 3 shows a modification of Fig. 2.

The projecting pole piece of the revolving field structure is illustrated in Fig. 1 as being built up out of two independent symmetrical halves 2, 3 fastened to the core 1 of the revolving field. Each half of the pole is provided with an end plate 4 at one end and a similar one 5 at the other end for holding the sets of laminæ 6 together. Fastening means of any desired form, as bolts 7, may be used. The pole halves 2, 3 are provided with dovetail projections 8, 9 which are adapted to coöperate with dovetail slots in the core 1 and to be held therein by means of wedges or keys 10, 11. It is however obvious that it is not necessary as far as the present invention is concerned that dovetail means be used for fastening the pole halves to the core and that any other suitable means may be employed.

The pole halves 2, 3 are preferably but not necessarily so constructed and related to each other that when they are assembled on the core 1 they will be juxtaposed but spaced apart to a desired extent. This slight spacing is to allow for any slight inaccuracy in the construction of the pole halves whereby the juxtaposed faces would not be precisely parallel.

The two pole halves 2, 3 may be provided with slots, cuts or recesses which when the pole halves are assembled, register to form hole 12; or this hole may be made wholly by drilling or boring. A spacing means here shown as a dowel or wedge 13 is shown as inserted in the hole 12 and is preferably a driving fit. The term spacing means as used in the claims is intended to cover a means which serves either to merely keep

the spaced parts from approaching each other a predetermined extent or to spread them apart, or both. For the sake of brevity the spacing means 13 will be hereinafter referred to as a dowel. After the dowel 13 is driven into the hole 12 the end plate, as for example 4, may be peened over as shown at 15. The end plates may be cored out or in any other manner constructed so as to 10 form a counter-sunk portion 17. In the form of the invention shown in Fig. 2 two dowel pins 13 are used of any desired length. The laminæ 6 may be provided with notches 14 so that when they are assembled in registration they form a portion of the hole 12. A hole of slightly larger diameter is then bored in any suitable manner into each end of the pole half through the end plate into the laminæ, the drill being selected so that 20 the dowel pins 13 will snugly fit the hole. As previously noted the dowel pins 13 may be held in the holes by any suitable means such as peening over the end plates.

The hole 12, is preferably near the air 25 gap end of the pole halves and it is to be understood that this location includes any one where the wedge or dowel will perform its desired functions.

It is however not necessary that two dowels 30 should be used and as shown in Fig. 3 a hole may be bored through from one end of the pole to the other and but a single dowel be used.

Pole pieces as above described are usually 35 shipped and handled with the energizing coil surrounding the pole halves and in order to prevent the pole halves slipping relatively to each other when so handled, as for example if a hold is taken on only one of the 40 dovetail projections, small dowel pins 16 are provided of any desired number. These dowel pins are conveniently inserted in holes in the sides of the end plates as clearly shown.

45 It will be noted that with the pole and method of constructing the same herein described it is possible to have each pole half or part tightly fastened to the revolving core without the transmission of fastening 50 stresses from one pole part to the other and yet to have the pole parts in intimate contact at the air gap end so that any unbalanced stresses arising in the two pole parts will react against each other.

55 It should be understood that it is not desired that the invention claimed be limited to the exact details of construction as shown and described for obvious modifications may occur to persons skilled in the art.

60 It is claimed and desired to secure by Letters Patent:

1. The method of constructing a pole piece comprising at least two parts which consists in fastening each part separately to a common support so that the parts are in juxtaposition but spaced apart and then inserting at least one spacing means between said parts near the air gap end of said parts.

2. The method of constructing a pole piece comprising at least two parts, which consists 70 in fastening each part separately to a common support so that the parts are adjacent each other, then boring at least one hole between said parts near the air gap end and then inserting at least one spacing means in 75 each hole.

3. In combination, a core, a pole for said core comprising a plurality of parts adjacent to and spaced from each other and at least one spacing means between said parts so near the air gap end.

4. In combination, a core, a pole for said core comprising a plurality of parts juxtaposed and spaced apart, said parts having registering slots in the juxtaposed faces and 85 at least one spacing means in said registering slots.

5. In combination, a core, a pole for said core comprising a plurality of parts juxtaposed and spaced apart, each part comprising 90 a set of laminæ and end plates, said end plates having registering slots in the juxtaposed faces and at least one spacing means in said registering slots.

6. In combination, a core, a pole for said core comprising a plurality of parts adjacent each other, means for fastening each part separately to said core, and at least one spacing means between said parts near the air gap end.

7. In combination, a substantially cylindrical core, a pole for said core comprising a plurality of parts, means for fastening each of said parts separately to said core at different circumferential points, and at least 105 one spacing means between said parts near the air gap end.

8. In combination, a core, a pole for said core comprising a plurality of adjacent parts, said parts having registering slots in 110 the adjacent faces, means for fastening each part separately to said core, and at least one spacing means in said registering slots.

9. In combination, a core, a pole for said core comprising a plurality of adjacent 115 parts, each part comprising a set of laminæ and end plates, said end plates having registering slots in the adjacent faces, means for fastening each part separately to said core, and at least one spacing means in said 120 registering slots.

10. In combination, a substantially cylindrical core, a pole for said core comprising a plurality of adjacent parts, each part comprising a set of laminæ and end plates, said 125 end plates having registering slots, means for fastening each part separately to said core and at least one spacing means in said registering slots.

11. In combination, a substantially cylind-

drical core, a pole for said core comprising a plurality of adjacent parts, each part comprising a set of laminæ and end plates, said end plates having registering slots means 5 for fastening each of said parts separately to said core at different circumferential points, and at least one spacing means in said registering slots.

12. In combination, a substantially cylindrical core, a pole for said core comprising a plurality of adjacent parts, said parts having registering slots in the adjacent faces, means for fastening each of said parts separately to said core at different circumferential points and at least one spacing means 15 in said registering slots.

13. A structure comprising a pole piece having separate parts, a coil surrounding said parts, and means comprising at least 20 one comparatively loosely fitting dowel disposed in and transversely between said parts

whereby relatively great movement of said parts in the general direction of the axis of said coil is prevented.

14. In combination, a core, a pole for said core comprising a plurality of adjacent parts, means for fastening each of said parts separately to said core and separate means associated with both of adjacent pole parts for equalizing bending stresses arising in 25 said parts.

15. In combination, a substantially cylindrical core, a pole for said core comprising a plurality of adjacent parts, means for fastening each of said parts separately to 30 said core at different circumferential points and separate means associated with both of adjacent pole parts for equalizing bending stresses arising in said parts.

In testimony whereof, the signature of the 40 inventor is affixed hereto.

ROBERT L. ALEXANDER.
